(57) **CLAIM**

The ornamental design for a control unit for medical interventional systems, as shown and described.

DESCRIPTION

FIG. 1 is a side perspective view of a control unit for medical interventional systems, showing my new design;

FIG. 2 is a top plan view thereof;

FIG. 3 is a bottom plan view thereof;

FIG. 4 is a side view thereof;

FIG. 5 is a side view thereof, opposite that shown in FIG. 4;

FIG. 6 is an end view thereof;

FIG. 7 is an end view thereof, opposite that shown in FIG. 6; and,

FIG. 8 is a top perspective view of a control unit for medical interventional systems, showing my new design in an exemplary environment.

The broken lines shown herein illustrate environmental matter and form no part of the claimed design.
